ELECTRON BEAM DEFLECTION SYSTEM

Alfred C. Schroeder, Feasterville, Pa., assignor to Radio Corporation of America, a corporation of Delaware

Application August 15, 1950, Serial No. 179,460

15 Claims. (Cl. 178—5.4)

This invention relates to deflection systems for cathode ray tubes. It has particular reference to systems for deflecting electron beams of kinescopes used in television systems.

The deflection of an electron beam of a cathode ray tube over a luminescent screen or other target electrode frequently is done in a manner to scan a substantially rectangular raster. Whether or not the raster is truly rectangular depends primarily upon the creation of two beam-deflecting component fields at right angles to one another. Any departure from this relationship results in a corresponding departure from the rectangular form of the scanned raster.

For many purposes, in television particularly, it is desirable to produce a scanned image raster which is substantially rectangular. Such a result is especially necessary in color television systems where a plurality of electron beams of one or more kinescopes are used. The beams are deflected over target electrode structure to reproduce an image in a number of its component colors. Good color registration may be obtained only if the rasters scanned by the beams are uniform in size and shape.

It is an object of the present invention, therefore, to provide an improved deflection system for an electron beam of a cathode ray tube, whereby the raster scanned by the beam has a predetermined shape irrespective of the relative orientation of the field-producing components of the deflecting system.

Another object of the invention is to provide an improved electron beam-deflecting system for each of a plurality of electron beams of one or more cathode ray tubes, whereby the respective image rasters scanned by the beams may be optically combined in substantially precise register.

Another object of the invention is to provide an improved electron beam-deflecting system for use in a color television image-reproducing system embodying a plurality of kinescopes, whereby the images formed on the kinescope screens all have substantially the same geometric shapes.

In the apparatus with which the invention is used, there is provided a deflecting system for an electron beam of a cathode ray tube. The deflecting system consists of two field-producing components. One of these components is energizable to deflect the beam substantially in a horizontal direction and the other substantially in a vertical direction. Means are provided for energizing these components with sawtooth wave energy. In accordance with a feature of this invention, there is provided means for energizing one of the field-producing components with supplemental wave energy which varies as a function of the energization of the other component. By such means there may be developed two beam-deflecting component fields which are substantially at right angles to one another. Accordingly, the beam may be deflected to scan a raster at a target electrode, such as a luminescent screen of a kinescope, which is substantially rectangular.

Further, in accordance with this invention, a plurality of electron beams of one or more kinescopes may be used to reproduce the component colors of an image. In such a case, certain ones or all of the electron beams may be provided with deflecting systems of the character described. Suitable adjustment of the deflecting systems may be made to control the sizes and shapes of the respective rasters formed on the kinescope target elec-

trode or screen structure. Uniformity of the sizes and shapes of these rasters will enable the optical combination of them to form a composite image in which all of the component color rasters are in substantially precise registration.

The novel features that are considered characteristic of this invention are set forth with particularity in the appended claims. The invention itself, however, both as to its organization and method of operation, as well as 10 additional objects and advantages thereof, will best be understood from the following description when read in connection with the accompanying drawings, in which:

Figure 1 is a block diagram of a color television signal-receiving and image-reproducing system embodying one form of the invention;

Figure 2 is a schematic circuit diagram of a component of the system shown in Figure 1 by which the supplemental deflecting wave energy is derived and coupled into the main deflection circuit; and,

Figure 3 is a fragmentary block diagram of another form of the invention.

Reference first will be made to Figure 1 of the drawings. This embodiment of the invention includes a conventional television receiver 11. The general details of

25 such a receiver are well-known to those skilled in the art. For the present purposes, therefore, it may be considered to include the necessary apparatus for amplifying and detecting a television carrier wave conveying the video signal and system control signals such as horizontal and vertical synchronizing pulses.

The present invention is not necessarily limited for use with any particular type color television system. It is particularly useful with systems of the simultaneous type such as disclosed in U. S. Patent No. 2,332,180

35 granted November 23, 1943, to A. N. Goldsmith and titled "Television System." In such a system the video signals representing individually the different component image colors are transmitted effectively over three different channels. Another type of system in which the invention may be used forms the subject matter of a copending application of John Evans, Serial No. 111,384, filed August 20, 1949, and titled "Color Television." In such a system video signals representing the different colors of each elemental image area are effectively transmitted and received consecutively.

40 Accordingly, it will be assumed that, regardless of the particular type of color television system used, there are made available at the receiver, video signals respectively representative of a plurality of image colors. For the

45 purpose primarily of illustration, it is further assumed that the present system is the usual three color one. In this case the color video signals will be representative respectively of the red, blue and green component color images. The individual video signal trains, therefore, may be considered to be conveyed separately from the television receiver 11 to the reproducing apparatus by red, blue and green video signal channels 12, 13 and 14, respectively. The video signal channels terminate at red, blue and green kinescopes 15, 16 and 17, respectively. It

50 will be understood that the video signals are impressed conventionally upon the intensity control electrodes of the electron guns of these kinescopes. Accordingly, the intensity of the electron beams produced by these guns is modulated in accordance with the particular video signals impressed thereon.

55 The color kinescopes 15, 16 and 17 are provided with systems for deflecting the respective electron beams thereof. It will be understood that these deflecting systems may be either electromagnetic or electrostatic. The invention is equally applicable to either type of system.

60 In the illustrative embodiments of the invention disclosed herein, electromagnetic beam-deflecting systems have been shown. Each consists of a vertical and a horizontal coil. These coils are mounted together about the neck of the kinescope in a conventional manner to form the usual deflection yoke. Since such yoke structures are well-known, they have been shown diagrammatically in the drawings. The red kinescope 15 is provided with vertical and horizontal deflecting coils 18 and 19, respectively. Similarly, the blue kinescope 16 has vertical and horizontal deflecting coils 21 and 22, respectively. Ver-

tical and horizontal deflecting coils 23 and 24, likewise, are provided for the green kinescope 17. The manner in which the horizontal and vertical coils of these deflecting systems are energized will be described presently.

In order to produce a composite image of the three component colors produced by the red, blue and green kinescopes 15, 16 and 17, respectively, there is provided a suitable optical system. The particular type of optical system which is employed is immaterial. For the purpose of the present disclosure, therefore, there is provided adjacent the luminescent screen of the green kinescope 17 a reflecting device such as a mirror 25. Adjacent to the screen of the blue kinescope 16 a color-selective mirror, such as a dichroic reflector or mirror 26, is provided. The properties of dichroic reflectors are well-known and will not be described in detail here. Suffice it to state that the dichroic mirror 26 has the property of reflecting blue light and of transmitting green light. A similar dichroic reflector 27 is mounted adjacent to the screen of the red kinescope 15. It has the property of reflecting red light and of transmitting blue and green light. Finally, there is provided a reflector such as a plane mirror 28 mounted in such position as to reflect all of the red, green and blue light incident thereon. This light may be projected onto a viewing screen or the kinescope screens may be viewed directly from the mirror 28. It will be understood that the kinescopes and optical components should be relatively located to equalize the lengths of the light paths from the kinescope screens to the mirror 28. By such means good optical registration may be effected.

In order to control the deflection of the electron beams of the kinescopes 15, 16 and 17 the television signal receiver 11 is coupled to a synchronizing signal separator 29. This apparatus may be entirely conventional. Its purpose is to separate the synchronizing signal pulses from the video signals. It further functions to separate the horizontal and vertical synchronizing pulses from one another. Accordingly, it may be considered to have two output circuits. In one output circuit the horizontal synchronizing pulses, such as indicated at 30, are developed. In the other output circuit vertical synchronizing pulses, such as shown at 31, are developed.

The synchronizing pulses 30 and 31 are impressed upon horizontal and vertical deflection generators 33 and 34. This apparatus also may be conventional. Each of the generators functions to produce sawtooth wave energy. The horizontal deflection generator 33 develops a sawtooth wave 35 having the horizontal or line-scanning frequency. Similarly, the vertical deflection generator 34 develops a sawtooth wave 36 having the vertical or field-scanning frequency.

The output of the vertical deflection generator 34 is coupled in parallel to corresponding terminals of the vertical deflection coils 18, 21 and 23. The other terminals of these coils are connected to ground. It will be understood, however, that in practice these terminals preferably are connected to individual vertical centering controls.

Similarly, the horizontal deflection generator 33 is coupled to corresponding terminals of the horizontal deflection coils 19, 22 and 24. The other terminals of these horizontal deflecting coils are returned to ground through individual compensating apparatus. Specifically, the horizontal deflecting coils 19, 22 and 24 are coupled respectively to compensating apparatus 37, 38 and 39. This apparatus will be understood to include individual horizontal centering circuits and means for developing supplemental wave energy varying as a function of the vertical deflecting wave energy. The details of typical compensating apparatus will be described subsequently in connection with Figure 2 of the drawings. For the present purpose, it is to be noted that the compensating apparatus 37, 38 and 39 is coupled for control to an intermediate point of the vertical deflection generator 34. At such a point there are developed from the synchronizing pulses such as 31, well-formed pulses which may be integrated to produce the sawtooth waves such as 36. These well-formed pulses are used to control the compensating apparatus and are indicated at 40.

Any misalignment of the horizontal and vertical coils forming a deflection yoke for any of the kinescopes will result in the scanning of a raster at the kinescope screen which is not entirely rectangular. Consider, for example, the kinescope 15. Unless the vertical and hori-

zontal coils 18 and 19, respectively, are mounted about the neck of the kinescope so as to produce horizontal and vertical beam-deflecting fields which are precisely at right angles to one another, the deflection of the beam over the screen of the tube will result in the formation of a nonrectangular raster. All opposite sides of the raster, nevertheless, will be substantially parallel. However, in accordance with this invention, there is introduced in the horizontal coil 19 a supplemental wave of a particular form and magnitude and having the vertical deflecting frequency. In this manner, the effect of any misalignment of the coils 18 and 19 may be overcome. Since each of the kinescopes is provided with deflection circuits of this character, it is seen that suitable individual control of the compensating wave energy will enable the production of rasters at the kinescope screens of similar shapes and sizes. Consequently, they may be combined by an optical system to produce a composite color television image in which the component color images all are in substantial registration.

It is to be noted that the compensating circuits generally used to correct for "keystone" or similar types of raster distortion where opposite sides are not parallel, are ineffective for present purposes. A typical Keystone correction circuit is shown in U. S. Patent No. 2,481,839, granted September 13, 1949, to A. N. Goldsmith entitled "Color Television." Such prior art compensating circuits do not provide the necessary generator of supplemental wave energy to be additively combined with the deflecting wave energy.

Referring now to Figure 2 of the drawings there will be described in some detail typical compensating apparatus for developing the supplemental wave energy. The compensating apparatus 37 used in conjunction with the red kinescope 15 has been chosen for illustration. It will be understood that similar apparatus may be used with the other color kinescopes. The apparatus consists of a wave-forming circuit including an electron tube 41. The control grid 42 of this tube is coupled by a capacitor 43 and a grid leak resistor 44 to the vertical deflection generator 34. The suppressor grid 45 is conventionally coupled to the grounded cathode. The screen grid 46 of this tube is connected to the junction point between voltage divider resistors 47 and 48. These resistors are connected between a point of positive potential and ground. The screen grid also is by-passed to ground by a capacitor 49. The tube 41 serves primarily to discharge a storage capacitor periodically in a manner to be described presently.

The anode of the discharging tube 41 is coupled to a storage capacitor 51. Such a connection is for the purpose of periodically discharging the capacitor through the tube 41. The capacitor is charged through a circuit which includes a resistor 52. This resistor is connected to a point of suitable positive potential. In the present case this potential is derived from a potentiometer 53 forming a part of a voltage divider which also includes a resistor 54. The voltage divider is connected between a source of positive potential and ground, as shown.

The storage capacitor 51 also is coupled to the control grid 55 of another electron tube 56 provided in the wave-forming circuit. Space current for the tube 56 is derived from a source of positive potential and is conducted through a load resistor 57 coupled to the anode and also through a cathode resistor 58.

The wave-forming circuit operates in the usual manner. The storage capacitor 51 is charged at a relatively slow rate which is determined primarily by its value and that of the resistor 52. Periodically, the discharging tube 41 is rendered operative under the control of the pulses 40 derived from the vertical deflection generator 34. Operation of this tube, whereby it becomes conducting, provides a relatively low impedance discharge path for the storage capacitor 51. The discharge of this capacitor, therefore, is at a rapid rate. Accordingly, there is developed at the ungrounded terminal of the capacitor a substantially sawtooth voltage wave which is impressed upon the tube 56 for suitable amplification.

The specific details of the wave-forming circuit are not to be considered as limiting the scope of the invention. The illustratively disclosed circuit functions to develop a wave having a substantially sawtooth shape. It will be understood by those skilled in the art that other wave forming circuits may be used within the scope of the invention for the development of waves hav-

ing other desired forms. One other wave form which may be developed for use in a system of the character described is a parabolic wave.

The sawtooth wave produced at the anode of the tube 56 is impressed upon an output electron tube 59 by means of a coupling including a capacitor 61 and a resistor 62. The control grid 63 of the tube 59 is connected to a variable point on the input resistor 62. The screen grid 64 of the tube 59 is coupled conventionally to a source of positive voltage. Similarly, the anode of the tube is connected to a positive voltage source through the primary winding 65 of an output coupling transformer 66. A relatively small resistor 67 is included in the cathode circuit of the tube 59. The transformer 66 also is provided with a secondary winding 68 in which the sawtooth wave energy is produced in a predetermined polarity dependent upon the connections of the primary and secondary transformer windings.

The secondary winding 68 of the coupling transformer 66 is connected to a polarity-reversing switch 69 to which also is coupled an output resistor 70. The resistor 70 is included in series with the horizontal deflecting coil 19 in its return circuit to ground. As previously described, this ground-return circuit includes a centering control which is diagrammatically illustrated as a potentiometer 71. The resistive portion of the potentiometer is connected between a point of positive voltage and ground. The sliding contact of the potentiometer is connected to the resistor 70 and also is bypassed to ground by a capacitor 72.

It is seen, therefore, that the sawtooth voltage wave developed by the compensating apparatus 37 at the vertical deflecting frequency is combined with the horizontal deflecting sawtooth energy derived from the generator 33 to energize the horizontal deflecting coil 19. The magnitude of the compensating wave may be controlled by adjustment of either of the sliding contacts associated respectively with the resistors 53 or 62. The polarity of the compensating sawtooth wave is determined by the position of the reversing switch 69. It will be appreciated that a misalignment of the vertical and horizontal deflecting coils in one sense requires a compensating wave of one plurality and misalignment in an opposite sense requires a compensating wave of opposite polarity.

A system of the character shown in Figure 1 ordinarily will be used mostly in those cases where each of the deflecting systems for the different electron beams is misaligned to the extent that the departure of the scanned image raster from a rectangular form is enough to be objectionable. It may be that the deflecting system for no one of the electron beams is precisely enough aligned to produce an exactly rectangular raster. However, it often will be found that at least one of these systems will be unobjectionable in this respect. In such a case it may be desirable to omit any compensating apparatus for this one deflecting system.

Figure 3 of the drawings, to which reference now will be made, shows diagrammatically such a system. It is assumed that the vertical and horizontal deflecting coils 18 and 19 associated with the red kinescope 15 are aligned satisfactorily relative to one another to produce a scanned image raster which is substantially rectangular. It may also be assumed that the deflecting systems of the blue and green kinescopes 16 and 17, respectively, are similarly aligned. However, if the misalignment of the deflecting system of the blue kinescope 16, for example, is in a sense opposite to any misalignment of the deflecting system for the red kinescope 15, the resultant mis-registration of the red and blue component images may be sufficient to be objectionable. In such a case it merely is necessary to effect compensation of one of the deflecting systems. The image rasters scanned correspond in shape and size to the other image raster.

Accordingly, in Figure 3 the vertical and horizontal deflecting coils 18 and 19 associated with the red kinescope 15 are energized solely by the sawtooth waves derived respectively from the vertical and horizontal deflection generators 34 and 33. The horizontal deflecting coil 22 associated with the blue kinescope 16 is further energized by supplemental wave energy derived from the compensating apparatus 38. Likewise, the horizontal deflecting coil 24 associated with the green kinescope 17 is additionally energized by supplemental wave energy produced by the compensating apparatus 39.

In view of the foregoing description of the operation

of the apparatus of Figure 1, taken in connection with the detailed disclosure of the compensating apparatus of Figure 2, the operation of the system of Figure 3 will be apparent to those skilled in the art. In this case, it will be understood that the compensating apparatus 38 is adjusted suitably to produce a scanned image raster by the electron beam of the blue kinescope 16 which conforms substantially to the shape and size of the raster scanned at the red kinescope 15. A similar adjustment of the compensating apparatus 39 is effected to produce the desired uniformity of the size and shape of the raster scanned at the green kinescope 17.

The compensating apparatus shown in detail in Figure 2 is especially adapted to produce supplemental wave energy having a substantially sawtooth shape. However, it will be understood to be within the scope of the present invention to provide apparatus for developing parabolic or other suitable wave shapes.

Furthermore, it also is contemplated to be within the scope of the invention that supplemental wave energy at the horizontal deflecting frequency may be introduced in the energizing circuits for the vertical deflecting components. Also, it will be apparent that the principles underlying the present invention may be successfully employed with a single deflecting system to produce a substantially rectangular or other desired shape of scanned raster.

In view of the two illustrative embodiments of the invention disclosed herein, it will be evident that the invention may be used successfully not only in color television systems, but also in black and white television systems. Moreover, it may be used in systems such as those including cathode ray oscilloscopes of a nature similar to the kinescopes of television systems. When the invention is to be used in conjunction with a plurality of deflecting systems, the supplemental wave energy may be supplied to all of the deflecting systems, in the case where it is desired to effect a compensation of all of the scanned rasters. Alternatively, where it is desired merely to make all of the rasters uniform, the supplemental wave energy may be impressed upon less than all of the deflecting systems. For example, it may be applied to all but one of the deflecting systems.

It also will be evident, in view of the present disclosure, that the invention is not limited necessarily for use in systems embodying a plurality of cathode ray tubes. Instead, the invention may be used in conjunction with a cathode ray tube having a composite target electrode structure and separate means to develop a plurality of electron beams. A representative form of such cathode ray tube apparatus is disclosed in U. S. Patent 2,491,839, granted September 13, 1949, to Alfred N. Goldsmith and titled "Color Television."

Furthermore, it will be appreciated by those skilled in the art that the invention may be employed beneficially in conjunction with the deflecting systems provided for video signal-generating tubes as well as with image-reproducing tubes as illustratively disclosed herein.

The nature of the invention may be determined from the foregoing disclosure of a number of illustrative embodiments thereof. The scope of the invention, in view of the disclosure and the immediately preceding paragraphs, is set forth in the appended claims.

What is claimed is:

- 65 1. In a color television system, cathode ray tube apparatus for reproducing an image in a plurality of component colors, said apparatus including means to develop an electron beam for each of said component image colors, and target electrode structure to be scanned by said beams, respective systems for deflecting said beams to scan individual rasters of said target electrode structure, each of said deflecting systems including individual components for effecting horizontal and vertical deflections of said respective beams, generators of deflecting wave energy at horizontal and vertical frequencies coupled respectively to normally energize said horizontal and vertical deflection system components, compensating apparatus including a generator of supplemental wave energy at one of said beam-deflecting frequencies, and means coupling said compensating apparatus to at least one of that group of deflecting system components which normally is energized at the other of said beam-deflecting frequencies in a manner to additively combine said supplemental energy and said normal beam-deflecting energy,
- 70
- 75
- 80
- 85

thereby to produce uniformity of shape and size of said scanned rasters.

2. Color television apparatus as defined in claim 1 wherein, said compensating apparatus includes one of said supplemental wave energy generators for each of said deflecting systems.

3. Color television apparatus as defined in claim 1 wherein, said compensating apparatus includes fewer of said supplemental wave energy generators than there are deflecting systems provided.

4. Color television apparatus as defined in claim 1 wherein, said compensating apparatus includes one less of said supplemental wave energy generators than there are deflecting systems provided.

5. Color television apparatus as defined in claim 1 wherein, said cathode ray tube apparatus comprises a plurality of kinescopes, each kinescope having an electron gun to develop one of said plurality of electron beams, and said target electrode structure comprising a luminescent screen associated with each of said electron guns.

6. In a color television system, a cathode ray tube for each of a plurality of component image colors, a luminescent screen for each of said tubes, an optical system to combine the images formed on said screens, each of said tubes also having a system for deflecting an electron beam to scan an image raster at each of said screens, said deflecting systems each including individual components for effecting horizontal and vertical beam deflection, wave generators coupled respectively to energize said horizontal and vertical deflecting system components, and generators of compensating wave energy at vertical deflecting frequency coupled to certain ones of said horizontal deflecting components in a manner to additively combine said compensating wave energy with said horizontal deflecting wave energy, thereby to produce uniformity of shape and size of said scanned image rasters.

7. A system for deflecting the electron beam of a cathode ray tube comprising, individual horizontal and vertical beam-deflecting components, individual generators to produce deflection wave energy respectively at horizontal and vertical scanning frequencies, means coupling said generators respectively to said beam-deflecting components, a generator of supplemental wave energy at one of said scanning frequencies, and means additively coupling said supplemental wave energy generator to that one of said beam-deflecting components which normally is energized at the other of said scanning frequencies.

8. In a system for electron beam deflection in cathode ray tube apparatus, two cathode ray tubes, each having means to develop an electron beam, a deflecting system for each of said tubes including individual horizontal and vertical beam-deflecting components, means to develop and impress respectively upon said beam-deflecting components wave energy at horizontal and vertical scanning frequencies, means to develop supplemental wave energy at one of said scanning frequencies, and means additively coupling said supplemental wave energy-generating means to those of said beam-deflecting components which normally are energized at the other of said scanning frequencies.

9. Cathode ray tube apparatus including, means to

develop two electron beams, individual horizontal and vertical beam-deflecting components for each of said beams, wave-generating means coupled to said beam-deflecting components to energize said beam-deflecting components at horizontal and vertical scanning frequencies respectively, means to develop supplemental wave energy at said vertical scanning frequency, and means additively coupling said supplemental wave energy-generating means to one of said horizontal beam-deflecting components to additionally energize said one horizontal beam-deflecting component as a function of said vertical scanning frequency.

10. Cathode ray tube apparatus including, means to develop a plurality of electron beams, individual horizontal and vertical beam-deflecting components for each of said beams, wave-generating means coupled to said beam-deflecting components to energize said beam-deflecting components respectively at horizontal and vertical scanning frequencies, means to develop supplemental wave energy at said vertical scanning frequency, and means additively coupling said supplemental wave energy-generating means to predetermined ones of said horizontal beam-deflecting components to additionally energize said predetermined horizontal beam-deflecting components at said vertical scanning frequency.

11. Cathode ray tube apparatus as defined in claim 10 wherein, said supplemental wave-generating means is additively coupled to all of said horizontal beam-deflecting components, whereby they are additionally energized at said vertical scanning frequency.

12. Cathode ray tube apparatus as defined in claim 10 wherein, said supplemental wave-generating means is additively coupled to all but one of said horizontal beam-deflecting components, whereby they are additionally energized at said vertical scanning frequency.

13. Cathode ray tube apparatus as defined in claim 10 wherein, said supplemental wave-generating means is additively coupled to two of said horizontal beam-deflecting components, whereby they are additionally energized at said vertical scanning frequency.

14. Cathode ray tube apparatus as defined in claim 10 wherein, three electron beams are developed, and said supplemental wave-generating means is additively coupled to two of said horizontal beam-deflecting components, whereby they are additionally energized at said vertical scanning frequency.

15. Cathode ray tube apparatus as defined in claim 10 wherein, three kinescopes are provided, said electron beam-developing means serving to generate individual electron beams respectively for said kinescopes, and said supplemental wave-generating means is additively coupled to at least one of said horizontal beam-deflecting beam components, whereby it is additionally energized at said vertical scanning frequency.
